CLAIM

The ornamental design for a wall file, as shown and described.

DESCRIPTION

FIG. 1 is a front perspective view of a wall file showing the new design wherein the moveable side pocket is shown on the right side;

FIG. 2 is a front elevational view thereof;

FIG. 3 is a rear elevational view thereof;

FIG. 4 is right side view thereof;

FIG. 5 is a left side view thereof;

FIG. 6 is a top thereof;

FIG. 7 is a bottom view thereof;

FIG. 8 is a front perspective view thereof wherein the moveable side pocket is shown on the left side; and,

FIG. 9 is a front perspective view thereof, showing the claimed design while in use, where the broken lines therein depict environmental matter that forms no part of the claimed design.
